UNITED STATES PATENT OFFICE.

MINNIE B. KENT, OF NEW YORK, N. Y., ASSIGNOR TO THE BUTTERICK PUBLISHING COMPANY, (LIMITED,) OF SAME PLACE.

DESIGN FOR A MISS'S COSTUME.

SPECIFICATION forming part of Design No. 18,335, dated May 22, 1888.

Application filed April 20, 1888. Serial No. 271,342. Term of patent 3½ years.

To all whom it may concern:

Be it known that I, MINNIE B. KENT, of the city, county, and State of New York, have invented and produced a new and original Design for a Pattern of a Miss's Costume; and I do hereby declare that the engraved prints accompanying this specification convey to any one accustomed to using paper patterns a clear understanding of how a garment made up by the pattern will appear.

The design shows a basque and a round walking-skirt. The skirt displays a flat drapery extending across the front gore and right side gore and falling in kilt plaits on the side 15 gore; a full panel on the left side gore that exhibits two deep clusters of smocking; a long tablier that falls to the edge in front of the full panel, is short at the right side, and displays draping plaits in its top; a full oval back drapery that displays draping plaits in its side

edges under a deep loose loop and bournous loops, and a fullness at the belt. The basque exhibits close-fitting fronts opening from the shoulders down over a full vest, that displays a V-cluster of smocking at the top and a band 25 cluster at the waist-line; a close-fitting back that exhibits underfolded plaits below the waist-line of the middle three seams, and the lower edge falling in jabot folds; full sleeves, displaying a cluster of smocking at the back 30 of the wrist, and a standing collar.

What I claim as my invention, and desire to secure by Letters Patent, is—

The design for a miss's costume, as shown in the engraved prints accompanying this specification. 35
